UNITED STATES PATENT OFFICE

117,952

DESIGN FOR A VENDING MACHINE

Arthur C. Haggstrom, Rockford, Ill., assignor to Raymond T. Moloney, Chicago, Ill.

Application April 19, 1939, Serial No. 84,378

Term of patent 7 years

To all whom it may concern:

Be it known that I, Arthur C. Haggstrom, a citizen of the United States, residing at Rockford, in the county of Winnebago and State of Illinois, have invented a new, original, and ornamental Design for a Vending Machine, of which the following is a specification, reference being had to the accompanying drawings, forming part thereof.

In the drawings, Figure 1 is a perspective view of the vending machine, showing my design;

I claim:

The ornamental design for a vending machine, as shown and described.

ARTHUR C. HAGGSTROM.
